Specification for Design.

Patented Nov. 16, 1920.

Application filed October 8, 1919. Serial No. 329,370. Term of patent 14 years.

To all whom it may concern:

Be it known that I, CHARLES G. DOUGLAS, a citizen of the United States, residing in Philadelphia, Pennsylvania, have invented a new, original, and ornamental Design for a Medal, Badge, Button, Pin, Ring, Flag, Banner, Pennant, or Article of Similar Nature, of which the following is a specification, reference being had to the accompanying drawing, forming part thereof, in which—

Figure 1 is a plan or face view illustrating my new and ornamental design embodied in a button, pin, or the like, and Fig. 2 is an elevation of the same.

I claim:

The ornamental design for a medal, badge, button, pin, ring, flag, banner, pennant, or article of similar nature, as shown.

CHARLES G. DOUGLAS.
